UNITED STATES PATENT OFFICE.

LOUIS N. TRUDEAU, OF DETROIT, MICHIGAN, ASSIGNOR TO AMERICAN CAN COMPANY,
OF NEW YORK, N. Y., A CORPORATION OF NEW JERSEY.

CAN-CRIMPING MACHINE

1,173,329.

Specification of Letters Patent. Patented Feb. 29, 1916.

Application filed November 24, 1913. Serial No. 802,611.

To all whom it may concern:

Be it known that I, LOUIS N. TRUDEAU, a citizen of the United States, residing in Detroit, county of Wayne, and State of Michigan, have invented a new and useful Improvement in Can-Crimping Machines, of which the following is a specification.

This invention relates to improvements in can crimping machines.

One object of the invention is to provide a crimping machine adapted for securing covers to non-circular cans in which one of the chucks for clamping the cans has provided therewith an integral guiding cam for the crimping roller, which cam corresponds in cross sectional shape to that of the can being operated upon.

Other objects of the invention are to provide a crimping machine of simple construction, parts of which may be readily interchanged to adapt the machine for operating on cans of different shape; to provide a crimping machine in which all the parts are thrown into operative position by a single means and in such order that the can is first clamped between the chucks, the power clutch and crimping roll being thrown into operation subsequent to the chucking.

The invention furthermore consists in the improvements in the parts and devices and in the novel combination of the parts and devices as herein shown, described or claimed.

In the drawing forming a part of this specification, Figure 1 is a side elevation of a machine embodying my improvements. Fig. 2 is a front elevation of the machine illustrated in Fig. 1. Fig. 3 is an enlarged detail sectional view taken substantially on the line 3—3 of Fig. 1. Fig. 4 is a broken sectional view taken substantially on the line 4—4 of Fig. 1. Fig. 5 is a vertical detail sectional view taken substantially on the line 5—5 of Fig. 2; and Fig. 6 is a vertical sectional view taken substantially on the line 6—6 of Fig. 5.

As shown in the drawing, the machine comprises a base or standard 10 from which extends an upright or supporting post 11, the latter having mounted therein in suitable bearings, a shaft 12 driven from any suit-

able source of outside power (not shown) through pulley 13 and clutch 14. The shaft 12 at one end thereof is provided with a bevel gear 15 meshing with a similar bevel gear 16 secured to a vertical chuck spindle 17, on the lower end of which is detachably mounted a combined chuck and cam A, described more in detail hereinafter. In alinement with the spindle 17 and below the latter is a vertically reciprocating lower chuck spindle 18 mounted in a suitable bearing 19 and having rotatably mounted therein a lower chuck or clamp plate 20. The spindle 18 is given reciprocating movement by means of an oscillatable lever 21 pivoted to a stationary part of the base 10, the lever 21 having pivotally secured thereto at its front end a collar 22 slidable on the spindle 18 and between which and another adjustable collar 23 on said spindle is placed a spring 24, thereby providing a yieldable connection between the lever 21 and lower chuck 20 to adapt the machine for operating on cans varying slightly in length. The lower chuck 20 is normally held in its lowermost position by a spring 25 secured to the frame and to the rear end of the lever 21. The clutch 14 and the lever 21 are operated by a foot treadle 26 pivoted to the standard 10 at 27, the treadle having pivotally connected therewith a link 28 also pivotally connected to the lever 21 and to a connecting rod 29, the latter and the link 28 having a pin and slot connection 30 therebetween to provide a certain amount of lost motion for a purpose hereinafter specified. To the upper end of the connecting rod 29 is pivoted a link 31, the latter in turn being pivoted to a slidable bar 32 mounted in suitable brackets 33. Adjustably secured to the bar 32 is a cam 34 which engages a pin 35 for throwing the clutch 14 into operative position.

Slidably adjustably mounted in a transversely extending recess 36 in the upright 11 is a box 37, the latter comprising a lower member 38 and a top plate 39 bolted thereto. The lower member 38 of the box 37 has a depending projection 40 threaded to receive an adjusting screw 41 adapted to be operated by a turn nut 42, by which means

the box 37 can be adjusted laterally of the machine. Within the box 37 is slidably mounted a slide 43 which carries a cam guide-roll 44 at its outer end. The slide 43 is yieldingly pressed outwardly by two springs 45 seated in suitable pockets in the slide, said springs at their inner ends engaging a depending plate 46 secured to the box 37. Also slidably mounted within the 10 box 37 and independently of the slide 43 is a crimping roll-carrying slide 47 which carries at its outer end a crimping roll 48 adapted to turn or crimp the flange of a can top 49 to secure it to a can body 50. 15 Pivottally connected to the inner end of the crimping roll-carrying slide 47 are links 51 forming a toggle with similar links 52, the latter being pivotally connected to a pivot 53 adjustably mounted in a slot 54 in an extension of the slide 43, the adjustment for the pivot pin 53 being accomplished by means of bolt and nuts 55. A pivot pin 56 connects the inner ends of the links 51 and 52 together and also to the link 31, the latter 20 being slidable within a tapered recess 57 in the extension of the slide 43, see Figs. 3 and 5.

The combined chuck and cam A comprises a lower plate 58 corresponding in shape to 30 and adapted to fit within the usual counter-sunk portion of the can top and a surface cam 59 formed integral with the plate 58. The combined chuck and cam is detachably secured to the lower end of the spindle 17 35 by a screw and nut connection indicated in dotted lines in Fig. 5, thereby adapting the chuck to be removed and replaced by another of different shape or size or both, it being understood that the cross sectional 40 shape of the chuck and cam will correspond to the cross sectional shape of the can being operated upon.

It sometimes happens that the cans being operated upon are not uniform in length on 45 all sides and to accommodate for such irregularities in the cans I mount on the chuck 20 what I term a universal movable supplemental chuck plate 61, the same having a socket 62 on its under side adapted to fit a 50 ball 63 mounted on the chuck 20. With this construction it will be apparent that the plate 61 can accommodate itself automatically to any irregularities in the lengths of the sides of the cans.

55 The operation is as follows: The operator first places the assembled can ends and can bodies on the lower chuck and then presses the treadle 26. The movement of the treadle 26 first causes the lower spindle 28 to move 60 vertically toward the upper chuck to thereby clamp or chuck the cans. The continued movement of the treadle 26 will in turn pull the connecting rod 29, thereby causing the clutch 14 to be thrown into operation and

also to project the crimping roll 48 into operative position, this latter result being effected by the straightening out of the toggle composed of the links 51 and 52. With the parts in this position, the can will be rotated and the slides 43 and 47 will be guided inwardly and outwardly and in accordance with the contour of the can by the surface cam 59, it being apparent that when the toggle controlling the slide 47 is straightened out, the slide 47 will move in unison with the 75 slide 43. Both slides will, of course, be always normally urged outwardly into operative position by the springs 45.

80 The adjusting screw 41 adapts the machine for operating on cans of different diameters; the adjusting screw 55 provides for the taking up of any wear on the parts connecting the slides 43 and 47; the adjustable cam 34 provides for variations of the time at which the clutch is thrown into operative position 85 after the chucking of the cans has taken place; and the interchangeable combined chuck and surface cam A adapts the machine for operating on cans of different cross sectional forms. 90

95 Although I have herein shown and described what I now consider the preferred embodiment of my improvement, yet it will be understood that various changes and modifications may be made without departing from the spirit of the invention, and all such changes and modifications are contemplated as come within the scope of the claims appended hereto.

I claim:

1. A can machine of the character described comprising, in combination: means for clamping and rotating an irregularly shaped can, said means including a combined chuck and rotary surface cam both corresponding in cross sectional shape to the cross sectional shape of the can being operated upon; and mechanism for uniting a can cover and can body together, said mechanism including a roll mounted on a carrying member, the latter being governed in its movements by said cam, substantially as specified. 110

2. A can machine of the character described comprising, in combination: means for clamping and rotating a can, said means including a pair of chucks movable axially relatively toward each other and one of which is provided with an integral rotary surface cam; and crimping mechanism for uniting a can cover and can body, said mechanism including a crimping roll mounted on a slidably carrying member, the latter being governed in its movements by said surface cam, substantially as specified. 120

3. A can machine of the character described comprising, in combination: rotatable and axially relatively movable chucks, one of which is provided with an integral

- rotary surface cam; a slide normally pressed into engagement with said cam and governed in its movements thereby, said slide having a crimping roller carried thereby and independently movable thereon; and means for moving said crimping roller into operative position after a can has been clamped between said chucks, substantially as specified.
- 10 4. A can machine of the character described comprising, in combination: upper and lower rotatable chucks, the lower chuck being axially movable relatively to the upper chuck and the latter having a rotary surface cam formed integrally therewith; a spring-pressed slide in engagement with and governed in its movements by said cam; and a crimping roll carried by said slide and movable in unison therewith in accordance with the movements imparted by said cam, substantially as specified.
- 15 5. A can machine of the character described comprising, in combination: means for clamping and rotating a can; crimping mechanism for operating on cans held by said means, said crimping mechanism including a reciprocating slide; a cam for governing the movements of said slide; and means for adjusting the path of reciprocation of said slide to thereby adapt the machine for operating on cans of different diameter, substantially as specified.
- 20 6. A can machine of the character described comprising, in combination: a pair of rotatable, relatively axially movable chucks; a spring-pressed slide having mounted thereon and independently movable thereof, a crimping roll-carrying slide; means governing the movements of said first named slide; and mechanism for moving the crimping roll-carrying slide relatively to the other slide and rendering them both movable simultaneously, substantially as specified.
- 25 7. A can machine of the character described comprising, in combination: chucks rotatable about a vertical axis and movable axially relatively to each other; crimping mechanism arranged in operative position relatively to said chucks, said crimping mechanism including a carrying slide; a cam governing the movements of said slide relatively to the chucks; and means for adjusting the path of reciprocation of said slide to thereby adapt the machine for operating on can bodies of different size, substantially as specified.
- 30 8. A can machine of the character described comprising, in combination: rotatable can clamping chucks movable axially relatively to each other; crimping mechanism normally in inoperative position; clutch mechanism for throwing said chucks into operation; means for moving the chucks to clamp the cans; a slide carrying the crimping mechanism; a toggle controlling said slide; and means connected with the toggle and with the clutch to throw the clutch mechanism and the crimping mechanism into operation; substantially as specified.
- 35 9. A can machine of the character described comprising, in combination: upper and lower rotatable chucks, the lower chuck being movable vertically relatively to the upper chuck; crimping mechanism arranged adjacent the upper chuck and normally in inoperative position; clutch mechanism controlling the transmission of power to the chucks and normally in inoperative position; means for first moving the lower chuck toward the upper chuck to thereby clamp a can therebetween; a toggle controlling the crimping mechanism; and means connected with the toggle and with the clutch to throw the clutch mechanism and the crimping mechanism into operative positions; substantially as specified.
- 40 10. A can-crimping machine comprising, in combination: a two-part can-rotating chuck adapted to grasp the can by axial movement of one of said parts; one of said parts having a cam corresponding in form with the contour of the can; a crimping roller adapted to operate on the can body flange; means for moving the crimping roller toward the can body; and means whereby the cam-shaped chuck member moves said crimping roller away from the axis of the can according to the contour of the can body.
- 45 11. A can machine of the character described comprising, in combination: upper and lower rotatable chucks, the upper chuck having formed integrally therewith a rotary surface cam and being interchangeable for others of different shape; and crimping mechanism including a slide yieldingly held in engagement with said cam and guided in its movements thereby, substantially as specified.
- 50 12. In a can crimping machine, in combination: a two-part can rotating chuck adapted to grasp the can by axial movement of one of said parts, one of said parts having a cam corresponding in form with the contour of the can; two radial slides, one carrying a crimping roller and the other carrying a roller adapted to bear on the cam surface of the rotary chuck member; and means for forcing said slides toward the can body and chuck.
- 55 13. In a can-crimping machine, in combination: a pair of aligned rotatable can clamping chucks, one of said chucks being movable axially relative to the other; one of said chucks being formed with a plate of non-circular contour adapted to engage the can

head, and being cam-formed above said plate to correspond with the contour of the can body where it is to be crimped; and the other of said chucks comprising a universally movable plate opposing the first mentioned plate.

Signed this 19th day of November, 1913,
in the presence of two witnesses.

LOUIS N. TRUDEAU.
